 New York, N. Y., a corporation of New York

Application August 31, 1944, Serial No. 552,164

11 Claims. (Cl. 235—61.7)

1

This invention relates to tabulating machines but more particularly to the type provided with automatic group control devices.

The broad object of the present invention is the provision of an automatic group control device enabling the customary initiation of total taking operations upon a change in group numbers when the group numbers follow in the desired sequence which includes a coordinated sequence checking device to verify the preliminary sorting, collating, and handling of cards.

To more fully understand the usefulness of the present invention, it is explained that in tabulating systems it is desirable to list groups of data derived from groups of tabulating cards with the data arranged according to a predetermined numerical sequence, either ascending or descending, depending upon the bookkeeping requirements. To this end, there is a preliminary sorting or collating of the tabulating cards by respective sorting or collating machines. Missorting by such machines is a rare occurrence, due to the present efficiency of such machines. An occurrence, however, will bring a card out of its numerical position. A frequent possibility of misplacement of a record exists in manually collating groups of cards as they are pulled out of the files, or sorting pockets and furthermore in the handling of cards before insertion in a supply hopper of tabulating machines.

Such "out-of-order" position or misplacement of a card may be effective to operate the automatic group control device to list its data and accompanying incomplete total on the result sheet out of its normal numerical position. Thus, if a card bearing the same group number again appeared, this would result in the listing of related data at a place removed from the related group, which, of course, is undesirable and contrary to the results required and obtainable from tabulating machines. It is only upon an examination of the erroneously printed result sheet that such out-of-order position of the listing can normally be detected. If the result sheet is unacceptable for this reason, rearrangement of the cards and a re-run of the latter through the tabulating machine is required, involving loss of time and delay in production of the correct result sheet.

It is, therefore, the main object of the invention to provide an automatic group control device and a coordinated sequence checking device which detects the out-of-order position of a card group with respect to its proper numerical position in a run of cards consisting of a plurality of successive groups.

2

Another object of the invention is to provide a record sequence checking mechanism effective during record controlled accounting operations to detect errors in sequence, and without requiring visual review of the result sheet when it is completed or considerably later when it is to be used for bookkeeping purposes.

A further feature of the invention is the provision of an automatic group control device and coordinated sequence checking device which enables normal total taking operations upon a change in group number, but renders the machine inoperable whenever the sequence checking device detects a deviation from the normal numerical sequence of the groups.

Another object of the invention is to provide a sequence checking device which suppresses further operations of the machine whenever the numerical progression of successive cards deviates from an ascending or a descending progression, depending upon the initial numerical progression of the card groups.

A further object of the invention is to provide a sequence checking device which prevents total taking operations whenever successive cards are not arranged in the numerical sequence that data groups are to be listed.

A still further object of the invention is to provide a sequence checking device which can be selectively conditioned to detect the deviation of a card away from an ascending or a descending numerical sequence of the card groups.

A still further object of the invention is to provide a simple and effective group control system which can be utilized apart from the previously referred to sequence checking device. For illustrative purposes the automatic group control system is shown herein in connection with a card controlled accounting machine but its embodiment can be varied and can be satisfactorily incorporated in other forms of machine where comparison of character data is required, such machines being, for example, sorting machines, collating machines, card punching machines, address printing machines, etc.

The present invention contemplates a system of automatic control wherein the control circuit which determines whether or not a change in the condition of the machine shall be effected is controlled from a system of magnets, two magnets A and B being provided for each controlling card column which are wired independently to each of the analyzing brushes for a given card column. These magnets cooperate with a duplex armature construction which is biased to hold the

contacts in the control circuit controlled by the armature closed when both magnets are energized concurrently. The duplex armature construction effects opening of the contacts if one magnet is energized while the other remains de-energized. As the cards feed beneath the separate analyzing brushes, the controlling contacts associated with each controlling column will remain closed as long as the perforations in the card column are identical on successive cards as in this case at each index point during the cycle, the two magnets will be energized or deenergized. If controlling perforations are different in the given column of two successive cards, at the time the first perforation is sensed the circuit of one of the magnets will be closed through said card perforation while the circuit of the other magnet remains open, thus permitting shifting of one of the duplex armatures to open the contacts of the control circuit.

The present construction obtains marked advantages over the differentially wound relay and other forms when used for group control purposes. Digressing to the former arrangement, it is well known that opposing coils are connected to the separate analyzing brushes and upon concurrent energization of the coils the common armature of such relay should remain at rest. In view of the energization from separate sources and through independent circuits wherein the circuit resistance may vary due to varying efficiency of contacts, potential differences give rise to corresponding flux density variations which will not insure static condition of the armatures when opposing coils are concurrently energized.

It is, therefore, an object of the invention to provide a comparing control relay structure that is not sensitive to potential differences and corresponding flux variations in the two magnets, and this object is preferably carried out by having the corresponding polepieces of both magnets associated with a common armature normally biased to provide differential airgaps.

The normal airgap, as is best understood by reference to Fig. 2 of the drawings, is disposed between each magnet A and B and one end of the armature it is to attract, whereas due to the angular position of the armature with respect to the polepiece surfaces, a much smaller gap, or none at all, is provided between the other end of the said armature and the corresponding polepiece of the other magnet. This enables the movement of a single armature when its related magnet is energized but through the polepiece of said magnet the other armature is maintained in its normal position. When magnets are provided with holding coils the continued magnetization of the polepieces will prevent the attraction of the moved armature and the unmoved armature by the subsequent energization of the magnet related to the unmoved armature. By this construction, the first magnet energized provides a superior control which is not unbalanced or changed in any way by the subsequent energization of another magnet. The potential differences or variations in flux density of polepieces of the two magnets can be varied over a very wide margin and this inherent feature insures the more positive and efficient operation of the group control system, when relays of the novel construction are utilized for this purpose.

Other objects of the invention will be pointed out in the following description and claims and illustrated in the accompanying drawings, which disclose, by way of example, the principle of the

invention and the best mode, which has been contemplated, of applying that principle.

In the drawings:

Fig. 1 is a wiring diagram of the circuits of a well known form of card controlled accounting machine having incorporated therein the automatic group control circuits controlled by the novel form of relay structure, said group control relays having additional contacts and sequence controlling circuits for detecting deviations from the normal sequence of group control numbers.

Fig. 2 is a detail showing the control magnets forming part of the improved control relays and the preferred arrangement of duplex armature and cooperating contacts.

Fig. 3 is a timing diagram outlining the timing of the cam operated contacts utilized in the circuit diagram.

The start and auto control circuits of the tabulating machine to which the present improvements are preferably applied are shown in Fig. 1 and a general description of the operation of the machine will be given, certain parts for clearer explanation being given more in detail than subordinate and relatively unimportant mechanisms.

For further explanation of details of construction and operation of the machine to which the present improvements are preferably applied, reference should be had to the patent issued to C. D. Lake et al., No. 1,976,617, dated October 9, 1934. Like reference numerals are used herein to designate similar parts of the patented machine.

In machines of this class, as more particularly explained in the aforementioned patent, it is customary to send the machine through a reset cycle of operation to insure that the accumulating devices are at zero and also to set up the automatic control mechanism forming part of the present invention. Suffice it to say at the present time that during the resetting operation motor control magnet 338 (Fig. 1) is energized and a holding circuit is provided for maintaining it energized. Contacts 338a of this relay will, therefore, be closed and contacts 338b open.

Starting circuit

The machine is now ready to start card feeding operations after cards have been placed in the feed magazine. Depression of the start key to close contacts ST will complete a circuit as follows: From line 334, cam contacts P1, tabulating clutch magnet 22, contacts 21, start relay 339, start key contacts ST, relay contacts 338b now closed, stop key contacts SP, contacts 338a (now closed), to line 335. Energization of magnet 22 will cause opening of contacts 21 and the circuit will now include relay magnet 340 which is wired in parallel with the contacts 21. Magnet 340 will close its contacts 340a to complete a circuit through the tabulating motor as follows: From line 334, motor TM, contacts 340a, to line 335, thus initiating the operation of the motor.

After the motor has operated through a portion of the cycle, cam contacts L1 close momentarily and complete a circuit from the line 334, wire 343, relay magnet 342, contacts L1, wire 344, contacts 340a, and to line 335. The consequent closure of contacts 342a will set up a holding circuit for the magnet 342, traceable from line 334, wire 343, magnet 342, contacts 342a, wire 344, contacts 340a, to line 335. Energization of the start relay magnet 339 will effect closure of its contacts 339a to set up a holding

circuit for the card feed clutch magnet 22 traceable from the line 334, cam contacts P1, magnet 22, relay 360, magnet 339, contacts 339a, wire 345, cam contacts L2, to line 335. Toward the end of this cycle, cam contacts L2 break and the machine will coast through the remainder of the cycle to home position, which is, as commonly known in the art, termed the "D" position. A second machine cycle is now initiated by depression of the start key to close contacts ST and a second cycle will follow in the same manner as the first. During this second cycle, the first card is advanced to the lower brushes and a second card is fed from the supply magazine to the upper brushes. Following this second cycle, the machine will, as fully described in the aforementioned patent, do one of two things: If the automatic resetting switch 346 is open, the machine will stop; if the automatic resetting switch is closed, the machine will automatically enter upon a resetting cycle of operation, not involved in the present operation.

It has thus been explained that the initiation of operations of the machine require first a resetting operation followed by two successive, manually initiated, tabulating cycles followed by a resetting cycle which may be automatically initiated. At this point, the first card is in readiness to pass and be analyzed by the lower brushes LB and the second card is in readiness to pass and be analyzed by the upper brushes UB and the automatic control mechanism is in readiness to compare the classification data of the cards as they pass through the machine.

Following the reset cycle just explained, the machine will, if automatic start switch 353 is closed, automatically enter upon card feeding and analyzing operations immediately upon completion of the last resetting cycle. This is brought about in the following manner: Relay contacts LCL_a will, by a circuit to be presently explained, have been closed, due to the arrival of the first card at the lower brushes LB and during the reset cycle cam contacts P2 close momentarily at the end of the cycle, thereby establishing a circuit from the line 335, contacts 338a, contacts SP, LCL_a and P2, switch 353, start relay magnet 339, contacts 27, tabulating clutch magnet 22, contacts P1, to line 334. The energization of magnet 22 will, as explained above, cause the machine to enter upon a tabulating cycle of operation during which the record cards are successively analyzed and data thereon entered into the recording device. Closure of lower card lever contacts 59 completes a circuit from line 335, contacts 59, wire 355, relay magnet LCL, wire 357, to line 334 to effect closure of contacts LCL_b and the closure of contacts LCL_a mentioned above. Closure of contacts LCL_b will complete a holding circuit for relay LCL through cam contacts L6. This circuit is from line 335, contacts L6, contacts LCL_b, magnet LCL, wire 357, to line 334. As long as record cards continue to pass the lower brushes LB, magnet LCL will remain continuously energized since contacts L6 are timed to be closed during the interval that the card lever contacts 59 open.

The upper card lever contacts 58 similarly complete a circuit from the line 335, contacts 58, magnet UCL, wire 357, to line 334. Closure of contacts UCL_b sets up a holding circuit through cam contacts L5 whose function and timing are the same as that of contacts L6.

Automatic group control circuits

The automatic group control circuits which

keep the machine in operation as long as group numbers on successively analyzed cards are the same will now be explained in detail.

The automatic group control circuits herein 5 are modified to work with the novel form of group control relays forming part of the present invention and such circuits in some respects are, therefore, slightly different from those embodied in the machine of Patent No. 1,976,617. The circuit 10 arrangement is alike for each denominational order and the description will be given in connection with one of such orders.

In the circuit diagram to avoid undue repetition of showing of the similar parts for showing 15 of the orders used in a commercial machine, the group control mechanism is shown herein for three denominational orders.

A number of relay magnets are provided, each 20 having a pickup winding 359 and a holding winding 360 and two of such relays are provided for each denominational order. Windings 359 associated with the upper brushes UB terminate in plugboard sockets 311 and the other pickup windings 359 of the same denominational order but 25 associated with the lower brushes LB terminate at plugboard sockets 313. Suitable plug connections may be made from such sockets, such as 316 and 317, to the plugboard sockets 300 and 301, respectively, of the controlling columns of 30 the LB and UB brushes, respectively. Since the index point positions on the card passing the lower brushes are analyzed concurrently with the analysis of the corresponding index point positions of the following card passing the upper 35 brushes, a perforation occurring in any index point position of both cards will complete a circuit at a time in the cycle corresponding to the location of the perforation.

Construction of group control relays

The construction of the group control relays 40 will be described with particular reference to Figs. 1 and 3, Fig. 1 showing the arrangement in diagrammatic form and Fig. 2 showing the details 45 of construction.

Differing from the group control relays of 45 Patent No. 1,976,617 wherein one control relay is provided for each card column, in the present case two magnets are provided for each card 50 column and each of said magnets has a pickup winding 359 and holding winding 360. The core is of a material and length so as to be magnetized by either of the windings 359 or 360 and extends 55 exteriorly of the windings to provide opposite polepieces 362 and 364. The A and B magnets of each relay are adjacently mounted so that the polepieces 362 are associated with a common armature 365 pivoted at 371 and with reference to the other polepieces 364, these are likewise 60 associated with a double armature 372 pivoted at 373. Each armature 365 and 372 operates buttons 374 of insulating material and abutting the longer contact blades of the A3 or B3 contacts and the intermediate longer contact blade of 65 the transfer contacts A1 and A2, B1 and B2.

Any suitable means may be provided to bias 70 the armatures 365 and 372 so that each normally rests against the polepiece of the magnet which is not adapted to rock the armature even though it attracts it. Preferably, the resiliency of said longer contact blades bias the armatures 365 and 372 to the normal position shown in the drawings.

Obviously, when the A magnet is energized in 75 any denominational order, since its polepiece 362

is separated from the cooperating end of the armature 365 by an appreciable airgap, the magnetic lines of force effective at said polepiece upon the energization of the pickup winding 359 will attract the cooperating end of the armature 365 to rock it about its pivotal point 371 and through the button 374 the related A contacts are operated. The holding winding 360, the circuits of which were previously described in detail, retains the armature 365 in its attracted and rocked position, maintaining the associated A contacts in their off-normal position. However, with reference to the polepiece 364 of the A relay, it will be observed that in the absence of the concurrent energization of the B magnet the armature 372 will be attracted by the polepiece 364 of the A relay but due to the absence of an airgap the contacts B3, B1 and B2 will be maintained in their normal positions, irrespective of the possibility of subsequently energizing the B relay magnet. Therefore, it should be noted that when one armature is rocked and held in attracted position by the holding coil, the other armature cannot be rocked although the other magnet is energized in a later point of the cycle. This construction makes it unnecessary to open the pickup circuit of the other magnet if its operation in a later point in the cycle would prevent the functions of the first magnet from being performed.

Obviously, the same condition obtains when the B relay magnet is energized ahead of the A magnet, in which case the armature 372 will be attracted and rocked by the polepiece 364 of the B magnet, to place contacts B1, B2 and B3 in their operated position and maintained in such position by the retained energization of the holding winding 360 of the B magnet. In such case, any impulse subsequently directed to the pickup winding 359 of the A magnet will be ineffective to rock the armature 372 since the polepiece 362 of the B relay is closer to the cooperating end of such armature 372 and will effectively hold it in the normal position.

In the above description it was assumed that one magnet, either A or B, was energized ahead of the other but it is apparent that upon identity of perforations analyzed by the UB and LB brushes, the pickup windings 359 of the A and B magnets will be concurrently energized. In such instance the polepiece 364 of the A magnet will magnetically hold the armature 372. Polepiece 362 of the B magnet will, with the same magnetic force, hold the armature 365 in its normal position. The equal magnetic force is derived by transmitting an electrical impulse of the same potential to the pickup windings of the A and B relay magnets preferably by having their windings equal as well as their cores of the same material to provide an equal magnetizing force for attraction of the armatures 365 and 372. However, there can be considerable variation in magnetic force without effecting any change in the position of the armatures, because of the relative differences in the airgaps interposed between the polepieces and the cooperating end of the common armature. In the case of the armature 365, the force of its attraction by the polepiece 362 of the B magnet will greatly exceed that created by the magnetized polepiece 362 of the A magnet, due to the smaller airgap between the polepiece 362 of magnet B and the armature 365. The same relation exists with regard to the polepieces 364 of the A and B magnets and the common armature 372.

Summarizing, the concurrent energization of the A and B magnets in each denominational column will retain the A1 and B1 contacts in normal closed position, whereas the energization of the A or B magnet, at a point in the cycle earlier than the energization of the other, will cause the opening of either A1 or B1 contacts in the automatic group control circuit, thereby conditioning the machine to take minor or major totals.

The novel construction of the present relay enables, by coordinated novel wiring connections, additional functions to be performed. One of the applications finds special use in tabulating machines to verify a predetermined sequence while taking group totals, allowing the machine to continue as long as cards pass through in the proper numerical sequence, either ascending, or descending. The novel construction of this part of machine will be described later and in connection with several examples.

Control pickup circuit

This circuit for the brushes UB is traceable as follows: From line 334, cam contacts L1A, LCLg card lever contacts, circuit breakers CB (not shown in detail but which are similar to circuit breaking devices 61), wire 361, upper brush contact roller 55, perforation in the card at the upper brushes, upper brush UB, plug socket 301, plug connection 317 to plug socket 311, pickup winding 359 and wire 363 to line 335. The control pickup circuit for the lower brushes is from the line 335, lower card lever contacts 59, circuit breaking devices 61, cam contacts L1B, lower brush contact roller 56, perforation in the card at the lower brushes, LB brush, plug socket 300, plug connection 316 to plug socket 313, pickup winding 359, wire 302 to line 334.

Control holding circuit

For convenience each automatic control relay which consists of the pickup winding 359 and the holding winding 360 will hereafter be designated as the A or B control relay. The A relay is the one associated with the UB brushes and the B relay for the same denominational order is the one associated with the LB brushes. This form of designation, while varying from that of Patent No. 1,976,617, will be found to be more convenient herein in tracing circuits controlled by such relays.

Energization of pickup winding 359 of each A relay before the energization of the pickup winding 359 of the B relay will close its holding contacts A3 and transfer certain other contacts, opening the normally closed A1 contacts and closing the A2 relay contacts. The closing of the A3 holding contacts of the A relay sets up a holding circuit for the holding winding 360 which circuit is from the line 334, wire 302, cam contacts L12, holding contacts A3, holding winding 360, wire 363 to line 335. Contacts L12 hold the windings 360 energized until the end of the cycle and until the mechanism has performed its controlling functions. It is thus apparent that the windings 359 are differentially energized in accordance with the value of the controlling perforation to close the A3 contacts and that the windings 360 of all the A relays keep their A3 contacts closed.

By a somewhat similar circuit, each B relay causes, when its pickup winding 359 is energized before the pickup winding 359 of the A relay is energized, the closure of the B3 holding contacts

and the transfer of other contacts to open the normally closed B1 relay contacts and close the normally open B2 contacts. The holding circuit for the holding coil of each B relay is from the line 334, wire 302, L12 cam contacts, winding 360 of the B relay, thence through the B3 holding contacts, wire 387 to line 335. It is thus apparent that a similar holding circuit is provided for the B relays for each denominational order.

After all the index point positions have been analyzed, the machine tests the setting of the A1 and B1 contacts for all denominational orders. If there is an agreement in all the controlling columns the A1 and B1 contacts for all denominational orders will have remained closed and a series circuit through such contacts will be closed. The contacts associated with the so-called minor controlling field of the record card will be grouped together and a plug connection 320 is made between the plug socket 312 and minor plug socket 314. This places the units order contacts A1 and B1 in the minor holding circuit. The plug connection 321 places the A1 and B1 relay contacts for the tens and hundreds orders in the major holding circuit. The ultimate object of the group control mechanism is to keep the motor control relay magnet 338 energized if there is agreement in both the minor and major control fields and to cause the energization of magnet 338 if there is a break or a disagreement in either of the two fields.

Minor and major holding circuits

The circuits for energizing the motor control relay magnet 338, the major control relay 370 and minor control relay 366 are substantially the same as in the aforementioned Patent No. 1,976,617 but are shown herein in simplified form, stripped of the various control switches embodied in the circuit of the patented machine.

Minor holding circuit

Magnet 338 is normally held energized through a circuit set up during the initial resetting cycle of the machine previously outlined in detail. During this cycle cam contacts P1 close and a circuit will be completed from the line 334, through cam contacts P7, minor control relay magnet 366, magnet 367 (not utilized in connection with the present circuit) wire 368, motor control relay magnet 338, wire 369, cam contacts L10, L9, wire 363 to the other side of the line 335. Minor control relay 366 closes its holding contacts 366a to establish a holding circuit from line 334, contacts 366a, minor control relay magnet 366, magnet 367, wire 368, motor control relay magnet 338, wire 369, cam contacts L10, L9, wire 363 to line 335. This circuit is called the minor holding circuit and remains energized as long as minor classification data on the record cards does not change.

Major holding circuit

Concurrently, the setting up of the minor holding circuit, the major holding circuit is also completed upon closure of cam contacts P7, the circuit being established from line 334, cam contacts P7, the major control relay magnet 370, cam contacts L9, wire 363, to line 335. Contacts 370a when closed, provide a holding circuit for the major control relay magnet 370 in parallel with the holding circuit of the minor control relay 366 and this circuit remains energized until there is a disagreement in the classification data of the major control field of the record cards.

If there is a change in the minor group number, the minor holding circuit alone is broken but if there is a change in the major group number, both the minor and the major circuits are automatically broken. This provides against the possibility of the major number changing and the minor group number remaining the same which would preserve the control circuit to magnet 338. During each cycle of the machine cam contacts L10 and L9 open momentarily. Since these contacts are in the minor and major holding circuits, respectively, these circuits would be interrupted at this time, if no path were provided around the contacts.

10 L10 and L9 open momentarily. Since these contacts are in the minor and major holding circuits, respectively, these circuits would be interrupted at this time, if no path were provided around the contacts.

Minor shunt circuit

During tabulating and listing cycles of the machine, contacts A1 and B1 of the denominational column or columns which are utilized to initiate minor total taking operations of the machine provide a shunt circuit around contacts L10 and L9. For example, the A1 and B1 contacts of the A and B relays, respectively, associated with the units column when both closed and when plug connection 320 is made, as shown, short circuit contacts L10, the short circuit running from the lower blade of contacts L10, wire 369, to the B1 contacts of the units column, thence to the A1 contacts of the same column, plug socket 312, plug connection 320, plug socket 314 to the upper blade of contacts L10.

Major shunt circuit

The major shunt circuit comprises the A1 and B1 contacts of the tens and hundreds columns used for controlling and short circuits contacts L9. The short circuit extends from the lower blade of contacts L9, plug socket 314, plug connection 320, plug socket 312, thence serially through the B1 and A1 relay contacts of the tens column and further serially through the B1 and A1 contacts of the hundreds column to plug socket 312, plug connection 321, plug socket 315, relay contacts UCLc, which are closed while cards are passing the upper brushes, to the upper blade of contacts L9. Thus, if at the time contacts L9 and L10 open and the control relays have registered agreement between the two cards analyzed, the minor and major holding circuits will be sustained through the A1 and B1 contacts of all controlling columns which remain in normal closed position. If, at such time, either the A1 or B1 contacts of the units column are open, the minor holding circuit would have been broken, deenergizing the minor control relay magnet 366 and the motor control relay 338, causing an automatic minor total taking cycle. If either of the contacts A1 or B1 of the tens and hundreds columns open, both the minor and major holding circuits would have failed to remain closed and the major control relay magnet 370 would also have been deenergized.

During the subsequent total taking cycle or cycles, the closure of cam contacts P7 will then again establish minor and major holding circuits and comparison of the successively fed record cards of the next group will take place and card feeding will proceed until there is a break in either of the circuits.

Means for detection of change in numerical sequence of group control numbers

It is well known that in card controlled accounting systems the controlling cards are preliminarily sorted according to their group num-

bers and each group may consist of one or more cards. The cards may be arranged, sorted or collated so as to have the groups arranged in an ascending or descending numerical sequence, in accordance with the bookkeeping or statistical requirements. In either sequence, data related to the groups will be printed on the result sheet in succession, according to the desired numerical sequence. It is desirable to detect the possibility that a controlling card deviates from the numerical sequence, which possibility may result from improper sorting, collation, or handling of the cards; error on the part of the operator in handling or collating the groups as they are taken from the files, sorting pockets, or for other reasons. The group control mechanism herein employed operates in the normal manner to cause minor or major total taking operations or both, depending upon the column in which change in numerical sequence takes place and also provides for continuous listing operations for successive cards which are alike in their group number. These normal operations of the machine have been previously described and to better understand one of the features of the invention the operation of the machine will be described in an exemplary manner. To exemplify, it will be assumed that the machine is conditioned to effect group control functions in an ascending numerical sequence and for simplicity it will be assumed that the group numbers consist of the following numbers: 22, 23, 24 and 25. Of course, each group may consist of one or more cards of the same group number, which prevents total taking operations until succeeding cards bear unlike group numbers. With the present arrangement, total taking operations will be effected only when the upper card bears a higher group number than the lower card. If the reverse condition obtains, the machine will be stopped and the operator will be signalled.

When group control operations are to be performed with the group numbers in the ascending numerical sequence, the switch S (Fig. 1) is positioned at A (ascending sequence) to make contact with a contact point 376. When the last card of the group bearing the group number 22 passes the lower brushes LB concurrently with the passage of the following card bearing the group number 23 by the upper brushes UB, it will be observed that with the punched holes fed past the brushes in the order 9, 8, 7, 6 . . . 0, the following card bearing the digit designation "3" in the units column will cause the A relay in the units column to be first energized and the A relay will be held energized by the stick circuit provided for its holding winding 360. When the 2 index point position of both cards is analyzed the perforation at the 2 index point position of the card passing the LB brushes will close a circuit to the pickup winding of the B relay of the units column, but such relay will be ineffective to rock the armature 372 because such armature is held attracted at this time by the polepiece 364 of the A relay of the units column. The opening of the A1 contacts of the units column will open the shunt circuit across the L10 contacts and the minor control relay will be deenergized, resulting in the taking of a minor total since the change is in the units column of the cards only. It is pointed out that since the tens digit of the tens column of both cards bears the same digit representation 2, both the A and B relays of the tens denominational order will be concurrently energized without any change in the position of their

respective contacts. This is also true of the "0" in the hundreds column. After taking the total, the tabulating or listing operations will proceed for all of the cards bearing the group number 23 and listing and total taking operations will be repeated in succession for the following groups up to the group numbered 25.

It will now be assumed that due to misfiling or mis-sorting, a card passes the upper brushes bearing the numerical designation 24 concurrently with the passage of the last card of the group bearing the number 25 and since card 24 represents a deviation from the ascending numerical sequence, the machine will function to detect this condition before a listing operation can be effected, under control of the card bearing the group numbered 24.

When the machine is conditioned for group control in ascending numerical sequence, a card containing a higher group number which is under control of the lower analyzing brushes LB always causes some B relay to be energized before the corresponding A relay. Under such circumstances, the B relay exercises a superior control to preferably prevent the normal total taking operation upon the change in group number. This will then enable interrupted listing operations to be resumed in the event that the card in error separates a group of cards in proper numerical sequence.

Considering now the possibility of a deviation from ascending sequence caused by the passing of a card bearing group number 24 by the upper brushes UB, concurrently with the passage of card bearing group number 25 by the lower brushes LB, under such circumstances the card passing the lower brushes will cause the energization of the B relay in the units order before the A relay in the units order is energized, since the first named card represents the higher digit. In the above example, this is obvious because the 5 digit representing perforation is analyzed by the LB brushes before analysis of the 4 digit representing perforation by the upper brushes UB. Since it is assumed that this change takes place in the units order in the above example, the B relay will be energized to close the B3 holding contacts to retain the B relay energized as long as the L12 cam contacts remain closed. Energization of the B relay will open the B1 contacts and close the B2 contacts, which latter have an additional function now to be described. The B1 contacts open the shunt circuit across the L10 contacts, attempting to condition the machine for a minor total taking operation which, as will be evident later, is inhibited. The closure of the B2 contacts enables a circuit to be closed from line 335, wire 363, UCLe contacts now closed, plug socket 315, plug connection 321, plug socket 312, thence through the A1 and B1 contacts of the hundreds order, thence through the A1 and B1 contacts of the tens order, thence through the A1 contacts of the units order, now closed because the previous energization of the B relay prevents the A relay from being effective to operate its contacts, thence through the B2 contacts of the units order, wire 377, switch contact point 376, switch lever of switch S, pickup winding of relay 380, wire 378, cam contacts L16, to line 334. Referring to Fig. 2, cam contacts L16 close just before L9—L10 open but during the time the L12 contacts remain closed to hold the B relay energized. A hold circuit for relay 380 is provided from the line 335, wire 381, through the holding winding of relay 380,

through the holding contacts 380a closed by the pickup winding, thence through a distinctive signal light 384, through the normally closed contacts 385 opened by manually operated button 386 to the line 334. The aforementioned circuit causes the maintained illumination of the distinctive signal light 384 which is visible to the operator to inform the latter of the deviation from the normal numerical sequence. The relay 380 opens contacts 380b which are in series with the SP or stop contacts so that when such contacts 380b are open the stop circuit of the tabulating machine will be open to terminate machine operations which would, under the above circumstances, be a following minor total taking operation. However, relay contacts 380c close and are wired in shunt with the L9—L10 contacts. Although the group control circuit is open, relay contacts 380c provide the shunt circuit and thus prevent conditioning of the machine to take any form of total, major, or minor. The signal light 384 and the stopping of the machine will effectively inform the operator so that the reason for the error can be detected. In the preceding example the occurrence of the card bearing the group number 25 at the LB brushes and the card bearing the group number 24 at the UB brushes prevented the taking of the total of group 24 which preceded the out-of-order card 25. Another out-of-order condition would be the passage of cards in groups 24, 25, 38 and 26. Card 38, with respect to card 25, is in an ascending sequence and normal operations will take place for this card as it passes the LB brushes. However, following card 26 indicates a descending sequence with respect to card 38 and with this deviation in sequence the detecting mechanism will operate, but preventing in this instance the taking of a total for the out-of-order card group 38. In either of the above cases the machine stops, this being a signal to the operator of the appearance of an out-of-order card. Further operations of the machine can be effected in various ways by the operator depending upon the manner of operation desired and how the error should be treated. In either case the depression of button 386 extinguishes the signal light 384 and deenergizes relay 380.

In the above example, it was assumed that there was a deviation from the normal ascending sequence and its detection was effected by the energization of the B relay before the A relay in the units order. Under other circumstances, this may be properly effected in the units order even though there is no deviation from the normal ascending numerical sequence. This will be observed in the passage of a tabulating card bearing the group number 130 past the UB brushes and concurrently a tabulating card bearing the group number 129 past the LB brushes. In the units order, the operation will take place as for the previous example. That is, the B relay will be energized before the A relay because 9 is sensed before 0. However, the digits of the tens order with respect to the cards passing the UB and the LB brushes occur in the ascending sequence and in the tens order a superior control will be exercised which will prevent the control by the units order from being effective.

Considering now the tens order, the A relay will be energized at the time that the 3 index point position of the card passing the UB brushes is sensed, thereby energizing the A relay before the 2 index point position of the card passing

the LB brushes is sensed. In the tens order group control circuit the A3 contacts will be closed to provide the holding circuit for the A relay. Concurrently, the A1 contacts will be opened and the A2 contacts will close. The closure of the A2 contacts will be ineffective for any control, since it is assumed that the machine is conditioned for detection of deviation from ascending numerical sequence. The opening of the A1 contacts will, however, open the circuit which would ordinarily be closed through the B2 contacts of the units order, wire 377, etc., when cam contact L16 closes, to cause the energization of the relay 380. Hence, the A1 contacts in the tens order exercises a superior control to prevent the energization of the relay 380 and the functions effected thereby.

It should also be understood that since there is, nevertheless, a change in group number digits in the tens order, the opening of the A1 contacts opens the shunt circuit across the L9 and L10 contacts to cause the deenergization of both the major control relay 370 and the minor control relay 366, thereby causing successive major and minor total taking operations to be carried out in the normal manner.

Detection of deviation from descending numerical sequence when machine is conditioned for group control in accordance with a descending numerical sequence

It is desirable at times to have the groups of data listed according to a descending numerical sequence and for the detection of deviation from descending numerical sequence the switch S is positioned to the D position (descending) so that its switch lever makes contact with contact point 382.

When groups of cards bearing the group numbers 24, 23 and 22 pass in succession through the machine, minor total taking operations are effected when successive cards are unlike in group numbers. With the numbers assumed in each case in the units order the B relay will be first energized when the higher digit is sensed by the LB brushes, preventing the effective operation of the A relay when a perforation is sensed in the next lower digit position in the following card under the UB analyzing brushes. The opening of the B1 contacts will open the shunt circuit to cause the minor total taking operations but the closure of the B2 contacts will be ineffective for signal purposes, due to the position of the switch S.

It will now be assumed that following the card contained in the group numbered 22, a card passes the UB brushes which contains the group number 23, which deviates from the descending numerical sequence. In this instance, the A relay in the units order will be energized to open the A1 contacts and to close the A2 contacts. There is no change in the position of the contacts in the hundreds and tens orders in this example and the opening of the A1 contacts will attempt to take a minor total. When L16 contacts close a circuit will be closed from line 335, wire 363, UCLe contacts now closed, plug socket 315, plug connection 321, plug socket 312, thence serially through A1 and B1 contacts of the hundreds order, thence serially through the A1 and B1 contacts of the tens order, thence through the A2 contacts of the units order now closed, wire 363, contact point 382, switch lever of switch S, pickup winding of relay 380, cam contacts L16 to line 334. Energization of the relay 380 will

cause the preceding described functions to be performed, namely, lighting of the lamp 384 and the opening of the stop circuit of the machine, and inhibition of a subsequent total taking operation. In other examples the A2 contacts of the tens or hundreds order will be effective to give the necessary indication if there is a deviation from the descending numerical sequence.

In the previous example it was pointed out that the energization of the A relay in the units order was the instrumentality for effecting the indication of a deviation from the descending numerical sequence. This is not necessarily the case for all examples as is exemplified when cards bearing group numbers 19 and 20 pass the UB and LB brushes concurrently. In the units order due to the analysis of the 9 digit ahead of 0, the A relay will be energized in the units order, which relay will be ineffective to give an indication of deviation because in the tens order the B relay is previously energized when the 2 index point position is sensed by the LB brushes. The opening of the B1 contacts in the tens order opens the energizing circuit of relay 380 and also the shunt circuit across contacts L9 and L10 to cause a major and minor total taking operation since the change in group designation occurs in the tens order. Other similar examples would be tabulating cards bearing the group numbers 130 and 129 passing the LB and UB brushes, respectively and concurrently.

The group control mechanism will function to take major and minor totals but the energizing circuit to relay 380 will be ineffective even though in the units order the numerical sequence deviates from a descending sequence. Another similar example would be cards representing 100 and 99 passing the LB and UB brushes, concurrently and respectively.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine controlled by records wherein successive record groups passing through the machine are supposedly arranged so that the serial numbers of said record groups conform to but may deviate from a predetermined serial numbering sequence, means for analyzing serial number representations on successive records, means controlled by said analyzing means for ascertaining whether successive records pertaining to successive record groups are unlike in serial number representations and have serial number representations which relatively conform to or deviate from the predetermined serial numbering sequence, control means controlled by said ascertaining means and rendered effective to initiate an operation when the serial numbers of successive record groups are ascertained to be unlike in value, and other means controlled by said ascertaining means to prevent the control means from being effective to initiate an operation when the serial numbers of successive record groups are ascertained to be unlike in value but deviate from the predetermined serial numbering sequence.

2. In a machine controlled by successive serially numbered record groups passed through the machine, supposedly arranged in a predetermined numerical sequence but where a following record group may deviate from the preceding record group in said numerical sequence, the combination of means for sensing control value representations on one record, and other means for sensing control value representations on a preceding record, means controlled by said sensing means for determining the relative magnitude of said pair of control values, total taking control means, means controlled by said determining means for causing the operation of said total taking control means when said pair of control values of successive records are determined to be unlike, and means controlled by said determining means to prevent the operation of said total taking control means upon determining that the control values of the successive records are unlike and the following record group deviates from the preceding record group in the predetermined numerical sequence.

3. In a machine controlled by records wherein successive record groups passing through the machine are supposedly arranged so that the serial numbers of said record groups conform to a predetermined serial numbering sequence, means for analyzing a serial numbering representation on one record and other means for analyzing the serial number representation on a following record, means controlled by said analyzing means jointly and responsive to the analysis of serial number representations on successive records for ascertaining whether one record has a serial number representation which is unlike and deviates from the other record in the predetermined serial numbering sequence or conforms to said serial numbering sequence, total taking control means, means controlled by said ascertaining means for causing the operation of the total taking control means when the serial numbers of successive records are ascertained to be unlike, and means controlled by said ascertaining means to prevent the operation of the total taking control means when the serial numbers of successive records are ascertained to be unlike but deviate from the serial numbering sequence.

4. In a machine controlled by records wherein successive record groups passing through the machine are supposedly arranged so that the serial numbers represented thereon conform to a predetermined serial numbering sequence, which machine includes an accumulator, and means to initiate a function under control of said accumulator, means for analyzing a serial number representation on one record and other means for analyzing the serial number representation on a following record, means controlled by said analyzing means jointly and responsive to the analysis of serial number representations on successive records for ascertaining whether the serial number representation of the following record deviates from a preceding record in said predetermined serial numbering sequence, or conforms to said predetermined serial numbering sequence, means controlled by said ascertaining means to cause the operation of said first named means upon ascertaining that the serial number of the following record differs from the serial number of the preceding record, and other means controlled by said ascertaining means to inhibit the operation of said last named means upon ascertaining a deviation in serial numbering sequence.

of the following record group with respect to the preceding record group.

5. In a machine controlled by records wherein successive record groups passing through the machine are supposedly arranged so that the serial numbers represented thereon conform to but may deviate from a predetermined serial numbering sequence, means for analyzing serial number representations on successive records, means controlled by said analyzing means for ascertaining whether successive records pertaining to successive record groups are unlike in serial number representations and have serial number representations which conform to or deviate from the predetermined sequence, means to control total taking operations, control means controlled by said ascertaining means for causing the operation of the total taking control means when the serial numbers of successive records are ascertained to be unlike in value, and other means controlled by said ascertaining means to prevent the control means from being effective to cause the operation of the total taking control means when the serial numbers of successive records are ascertained to be unlike in value but deviate from the predetermined serial numbering sequence.

6. In a machine controlled by records wherein successive records passing through the machine are supposedly arranged in record groups so that the serial numbers represented thereon conform to a predetermined ascending or descending serial numbering sequence, but may deviate from either of said serial numbering sequences, means for analyzing serial number representations on successive records, means controlled by said analyzing means for ascertaining whether successive records have unlike serial number representations and deviate from the ascending or descending sequence, means to control total taking operations, means controlled by said ascertaining means for causing the operation of the total taking control means when the serial numbers of successive record groups are ascertained to be unlike, means controlled by said ascertaining means to prevent the operation of the total taking control means when the serial numbers of successive record groups are ascertained to be unlike but deviate from the ascending serial numbering sequence or to prevent the operation of the total taking control means when the serial numbers of successive record groups are ascertained to be unlike and deviate from the descending serial numbering sequence, and means for selectively causing said ascertaining means to effect the operation of said total taking preventing means either upon a deviation of successive record groups from an ascending serial numbering sequence or a descending numbering sequence.

7. In a machine controlled by records arranged in groups wherein successive records passing through the machine are supposedly arranged so that the serial numbers of record groups conform to a predetermined serial numbering sequence but may deviate therefrom, which includes means to initiate and effect operations under control of records, and total taking control means, means for analyzing successive records for determination of serial number representations thereon, means controlled by said analyzing means for ascertaining whether a serial number representation of a following record is alike or unlike with respect to a preceding record, and when unlike deviates from said pre-

determined serial numbering sequence or conforms to said serial numbering sequence, means controlled by said ascertaining means to enable the operation of the initiating and effecting means to cause operations under control of records upon ascertaining that the serial numbers of successive records are alike, and to initiate the operation of said total taking control means upon ascertaining that serial numbers of successive record groups are unlike, and means controlled by said ascertaining means to prevent the operation of said total taking control means upon ascertaining that serial numbers of successive record groups are unlike but deviate from the predetermined serial numbering sequence.

8. In a machine controlled by records arranged in groups wherein successive records passing through the machine are either alike or unlike in their control values and when unlike are supposedly arranged so that the serial numbers of said record groups conform to an ascending or descending serial numbering sequence but may deviate from either of said sequences, which machine includes means to initiate and effect operations under control of records and total taking control means, means for analyzing serial number representations on successive records, means controlled by said analyzing means for ascertaining whether a serial number representation of a following record is alike or unlike with respect to the control values of a preceding record, and when unlike deviates from either an ascending or descending serial number sequence or conforms to either an ascending or descending serial number sequence, means controlled by said ascertaining means to enable the operation of the initiating and effecting means to cause operations under control of records upon ascertaining that the serial numbers of successive records are alike, and to initiate the operation of said total taking control means upon ascertaining that serial numbers of successive record groups are unlike, means controlled by said ascertaining means to prevent the operation of said total taking control means when the serial numbers of successive record groups are ascertained to be unlike and deviate from the descending or ascending serial number sequence, and means for selectively causing said ascertaining means to effect the operation of said means to prevent the operation of said total taking control means either upon a deviation of successive record groups from an ascending serial number sequence or a deviation from a descending serial number sequence.

9. In a record controlled machine, the combination of a pair of magnets, each having a pickup winding and a holding winding, a corresponding number of armatures, each pivoted intermediate the adjacent poles of said magnets and both armatures so biased and arranged with respect to the poles of said magnets that opposite ends of both armatures have airgaps with different magnets to cause the attraction and rocking of each armature when the pickup winding of the related magnet having the airgap is energized, and other ends of both armatures have no airgaps, or substantially none, with said magnets to cause the attraction but not rocking of each armature when the pickup winding of the related magnet having no airgap is energized, means for transmitting differentially timed electrical impulses representing equal or unequal values to said pickup windings, whereby both pickup windings, upon being energized at the same time by simultaneous transmission of equal

digit representing electrical impulses thereto, will cause both armatures to be attracted but not rocked by the poles not having the airgaps, and upon energization of one pickup winding before the other by dissimultaneous transmission of unequal digit representing impulses the first energized pickup winding will attract and rock the armature with which its polepiece has an airgap and will attract but not rock the other armature with which its other polepiece has no airgap, and means controlled by each armature when rocked to energize and maintain the energization of the holding winding related to the energized pickup winding that attracts and rocks the armature, whereby each energized holding winding will maintain and hold the rocked armature in rocked position and the other armature if unrocked in unrocked position.

10. In a record controlled machine, the combination of a pair of magnets, each having a winding, a corresponding number of armatures, each pivoted intermediate the adjacent poles of said magnets and both armatures so biased and arranged with respect to the poles of said magnets that opposite ends of both armatures have airgaps with different magnets to cause the attraction and rocking of each armature when the winding of the related magnet having the airgap is energized, and other ends of both armatures have no airgaps, or substantially none, with said magnets to cause the attraction but not rocking of each armature when the winding of the related magnet having no airgap is energized, and means for transmitting differentially timed electrical impulses representing equal or unequal values to said windings, whereby both windings upon being energized at the same time by simultaneous transmission of equal digit representing electrical impulses thereto will cause both armatures to be attracted but not rocked by the poles not having the airgaps, and upon energization of one winding before the other by dissimultaneous transmission of unequal digit rep-

resenting impulses the first energized winding will attract and rock the armature with which its polepiece has an airgap and will attract but not rock the other armature with which its other polepiece has no airgap.

- 5 11. In a machine controlled by records wherein successive record groups passing through the machine are supposedly arranged so that the serial numbers of said record groups conform to but may deviate from a predetermined serial numbering sequence, means for analyzing serial number representations on successive records pertaining to successive record groups, means controlled by said analyzing means for ascertaining and detecting whether successive records pertaining to successive record groups have serial number representations which are unlike and relatively conform to or deviate from the predetermined serial numbering sequence, control means controlled by said ascertaining means and rendered effective to initiate an operation when the serial numbers of successive record groups are ascertained to be unlike, and means controlled by said ascertaining means for manifesting when the serial numbers of successive record groups are ascertained to be unlike but deviate from the serial numbering sequence.
- 10 12. In a machine controlled by records wherein successive record groups passing through the machine are supposedly arranged so that the serial numbers of said record groups conform to but may deviate from a predetermined serial numbering sequence, means for analyzing serial number representations on successive records pertaining to successive record groups, means controlled by said analyzing means for ascertaining and detecting whether successive records pertaining to successive record groups have serial number representations which are unlike and relatively conform to or deviate from the predetermined serial numbering sequence, control means controlled by said ascertaining means and rendered effective to initiate an operation when the serial numbers of successive record groups are ascertained to be unlike, and means controlled by said ascertaining means for manifesting when the serial numbers of successive record groups are ascertained to be unlike but deviate from the serial numbering sequence.
- 15 13. In a machine controlled by records wherein successive record groups passing through the machine are supposedly arranged so that the serial numbers of said record groups conform to but may deviate from a predetermined serial numbering sequence, means for analyzing serial number representations on successive records pertaining to successive record groups, means controlled by said analyzing means for ascertaining and detecting whether successive records pertaining to successive record groups have serial number representations which are unlike and relatively conform to or deviate from the predetermined serial numbering sequence, control means controlled by said ascertaining means and rendered effective to initiate an operation when the serial numbers of successive record groups are ascertained to be unlike, and means controlled by said ascertaining means for manifesting when the serial numbers of successive record groups are ascertained to be unlike but deviate from the serial numbering sequence.
- 20 14. In a machine controlled by records wherein successive record groups passing through the machine are supposedly arranged so that the serial numbers of said record groups conform to but may deviate from a predetermined serial numbering sequence, means for analyzing serial number representations on successive records pertaining to successive record groups, means controlled by said analyzing means for ascertaining and detecting whether successive records pertaining to successive record groups have serial number representations which are unlike and relatively conform to or deviate from the predetermined serial numbering sequence, control means controlled by said ascertaining means and rendered effective to initiate an operation when the serial numbers of successive record groups are ascertained to be unlike, and means controlled by said ascertaining means for manifesting when the serial numbers of successive record groups are ascertained to be unlike but deviate from the serial numbering sequence.
- 25 15. In a machine controlled by records wherein successive record groups passing through the machine are supposedly arranged so that the serial numbers of said record groups conform to but may deviate from a predetermined serial numbering sequence, means for analyzing serial number representations on successive records pertaining to successive record groups, means controlled by said analyzing means for ascertaining and detecting whether successive records pertaining to successive record groups have serial number representations which are unlike and relatively conform to or deviate from the predetermined serial numbering sequence, control means controlled by said ascertaining means and rendered effective to initiate an operation when the serial numbers of successive record groups are ascertained to be unlike, and means controlled by said ascertaining means for manifesting when the serial numbers of successive record groups are ascertained to be unlike but deviate from the serial numbering sequence.
